UNITED STATES PATENT OFFICE.

IRVING McC. BEAN, OF MILWAUKEE, WISCONSIN; MABEL WEBSTER BEAN, EXECUTRIX,
AND FIRST TRUST COMPANY, EXECUTOR, OF SAID IRVING McC. BEAN, DECEASED.

BATH-CABINET.

1,301,029.

Specification of Letters Patent. Patented Apr. 15, 1919.

Application filed May 22, 1915. Serial No. 29,725.

To all whom it may concern:

Be it known that I, IRVING McC. BEAN, a citizen of the United States, residing at 629 Wells Bldg., Milwaukee, in the county 5 of Milwaukee and State of Wisconsin, have invented new and useful Improvements in Bath-Cabinets, of which the following is a specification.

This invention relates to shower bath cabinets or stalls.

The object of the invention is to provide a simple, light, efficient, durable, non-leakable shower bath cabinet or stall which may be easily manufactured and readily installed.

Various other objects and advantages will hereinafter appear.

The invention as preferably embodied comprehends a shower bath cabinet having 20 the side walls formed of a single piece of metal whose vertical edges are spaced apart to provide an entrance, and a bottom formed of a single piece of metal, the two being united by a non-leakable joint.

25 The ordinary cabinet made from stone slabs must be erected upon a strong rigid foundation so as to lessen the possibility of the slabs becoming separated and a leakage basin must be arranged underneath the same on account of this liability to leak.

30 The cabinet provided by this invention may be set upon any simple foundation and no leakage basin is required. The walls have no vertical joints and the entire structure is unitary and complete.

35 The accompanying drawings illustrate a cabinet embodying the invention.

The views in the drawings are as follows:

40 Figure 1 is an elevation of a shower bath cabinet showing the entrance opening therein.

Fig. 2 is a plan view thereof.

45 Fig. 3 is a perspective view of the shell forming the sides of the cabinet.

Fig. 4 is a perspective view of the bottom member of the cabinet.

Fig. 5 is a cross section through the entrance sill.

50 The cabinet comprises, in general, walls or a shell 1 and a bottom 2, each of which is a single metal piece. These pieces are preferably made from sheet metal bent or pressed into the required shape.

55 The metal piece forming the walls has its

vertical edges separated to provide an entrance. The edges are bent back to form posts 3.

The walls are provided with suitable holes 4 for shower fixtures or any other accessories.

The bottom has its outer edge bent into an upwardly extending flange 5 to form a basin in which the side walls set. The top edge of the basin is outside of and above 65 the lower edge of the side walls so that the water flowing down the walls cannot escape from the cabinet except through the outlet. There is thus, in effect, provided a non-leakable connection or joint between the side 70 walls and the bottom.

The bottom is preferably permanently fastened to the walls and to accomplish this the flange may be crimped, soldered, brazed, welded or otherwise united to the walls.

75 The flange preferably has a straight portion 6 between the posts, and over the edge of this straight portion is fitted a split tube 7 which forms a smooth sill.

The bottom is inclined downwardly to a 80 central outlet 8 so that the water will readily run out of the cabinet.

The walls are provided with slots 9 at the entrance posts to receive the flange 5.

The upper vertical edges of the walls 85 may be connected by a cross brace 10 to strengthen the structure.

Of course, a top or cover may be provided, and such top may be made in any suitable way, but all that is required to form a complete cabinet is the walls and the bottom.

The ordinary cabinet made from stone slabs must be erected upon a heavy foundation so as to lessen the danger of the slabs settling and causing leaks at the joints. 95 Even when erected on a heavy expensive foundation the cabinets are so liable to leak that a leakage basin must be arranged underneath them.

The cabinet provided by this invention is 100 simple, light, efficient, durable, inexpensive and non-leakable. It may be set upon any simple foundation and a leakage basin need not be provided. It is formed from simply two pieces of metal and there is no danger of a leak at the joint between the walls and the bottom. This cabinet further has the advantage that it is a unitary structure which is complete in itself and may be bodily installed, thereby making its cost of in- 110

stallation far less than those cabinets formed from slabs which have to be set in position and joined together.

In order to give the cabinet a smooth, finished, non-corrosive surface it is preferably painted or enameled.

Fig. 2 shows the cabinet set behind the wall of a room. The walls shown in dotted lines extend up to the entrance and the door 10 posts 3 set on the outside of the walls.

The particular cabinet shown in the drawing and described herein has been selected merely for the purpose of illustrating and disclosing the invention so it will be understood that this cabinet may be modified in various ways without in any way departing from the invention as defined from the claims appended hereto.

Having thus described my invention, what 20 I claim and desire to secure by Letters Patent is,

1. A shower bath cabinet comprising, a single sheet of metal bent to form the side walls and having its vertical edges spaced apart to provide an entrance, and a one piece metal bottom in the form of a basin in which the side walls set.

2. A shower bath cabinet comprising, a single sheet of metal bent to form the side 30 walls and having its vertical edges spaced apart to provide an entrance, and a one piece sheet metal bottom having its edge formed into a flange which over-lies the side walls and is attached thereto to provide a unitary structure.

3. As a new article of manufacture, a shower bath cabinet having a single metal sheet bent to form the walls, the edges of said sheet being spaced to form an entrance, 40 and a one-piece bottom made from a single metal sheet the edges of which are bent upward to fit over the outside of the lower edges of the walls to form a non-leakable joint.

45 4. As a new article of manufacture a complete unitary shower bath cabinet made from sheet metal and having one-piece walls formed from a metal sheet bent into the required shape and having its vertical edges spaced apart to form an entrance, and a one-piece bottom formed from a single sheet of metal inclined downwardly to an outlet at its center and having its edges bent up to form a flange which fits over the outside 50 lower edges of the walls to unite the bottom to the walls and make a non-leakable joint.

5. As a new article of manufacture a complete unitary shower bath cabinet made from sheet metal and having one-piece 60 walls formed from a metal sheet bent into the required shape and having its vertical edges spaced apart to form an entrance, and a one-piece bottom formed from a single sheet of metal inclined downwardly to an outlet at its center and having its edges bent 65

up to form a flange which fits over the outside lower edges of the walls to unite the bottom to the walls to make a non-leakable joint, and a cross-piece extending across the entrance at the top to connect the vertical 70 edges of the walls.

6. A unitary sheet metal bath cabinet having its walls formed from a single sheet metal piece bent into the required shape and having its vertical edges separated to provide an entrance, said edges being bent back to form posts and stiffen the wall, and a one-piece bottom formed from a single sheet metal piece inclined downwardly to an outlet at its center and having its edges bent 75 up to form flanges which fit over the outside of the lower edges of the walls to make a non-leakable joint.

7. A unitary sheet metal shower bath cabinet having its walls formed from a single sheet metal piece bent into the required shape and having its vertical edges separated to provide an entrance, said edges being bent back to form posts and stiffen the wall, and a one-piece bottom formed 80 from a single sheet metal piece inclined downwardly to an outlet at its center and having its edges bent up to form flanges which fit over the lower edges of the walls to make a non-leakable joint, and a metal strip fitting over the flange at the bottom 85 of the entrance to provide a sill.

8. A new article of manufacture comprising a sheet metal shower bath cabinet having its walls formed from a single sheet of 90 metal bent into cylindrical shape and a circular bottom member formed from a single sheet of metal and having an upstanding flange adapted to fit over the lower edges 95 of the walls on the outside thereof and to be attached thereto whereby a unitary structure is obtained.

9. A unitary sheet metal shower bath cabinet having its side walls formed by a single piece sheet metal member bent into cylindrical shape with the edges of said sheet spaced to form an entrance opening, said edges being bent back to form entrance posts and stiffening portions which may be attached to a wall to support the cabinet 100 and a circular bottom member formed from a single piece of sheet metal and having a peripheral flange fitting over the lower edge 110 of the walls on the outside thereof and attached thereto.

10. A sheet metal shower bath cabinet having a circular bottom member formed out of a single piece of sheet metal with an upstanding peripheral flange having a straight portion, a split metal tube covering the edge of the straight portion of said flange to form an entrance sill and a single piece sheet metal member bent into cylindrical shape with the edges of said sheet spaced to form an entrance opening, said 115 120 125 130

latter member being adapted to fit within said flange and to be attached thereto whereby a unitary, non-leakable structure is obtained.

- 5 11. A unitary sheet metal shower bath cabinet having its side walls formed by a single piece sheet metal member bent into cylindrical shape with the edges of said sheet spaced to form an entrance opening,
- 10 said edges being bent back to form entrance posts and stiffening portions which may be attached to a wall to support the cabinet and a circular bottom member formed out of sheet metal with an upstanding peripheral flange having a straight portion, a split metal tube covering the straight portion of said flange to form an entrance sill, said flange fitting over the lower edges of the walls on the outside thereof and being attached thereto.
- 15 12. As a new article of manufacture a

shower bath cabinet having the walls thereof formed from a single piece of metal and a bottom member formed from a single piece of metal and united with the walls by a 25 non-leakable joint, said walls and bottom member being adapted to be readily positioned for use as a unit.

13. A shower bath cabinet comprising side walls formed of a single piece of metal 30 whose vertical edges are spaced apart to provide an entrance, and a bottom formed of a single piece of metal and united to the side walls by a non-leakable joint.

In witness whereof, I have hereunto subscribed my name in the presence of two witnesses.

IRVING McC. BEAN.
